JACQUARD CARD PUNCHING MACHINE

John Schull, Willow Grove, Pa.

Application January 5, 1932, Serial No. 584,835

16 Claims. (Cl. 164—114)

This invention relates to jacquard card punching machines, and more particularly to machines of the repeating type such as that shown and described in U. S. Letters Patent No. 304,864, issued to Vernon Royle and John Royle, Jr., under date of September 9, 1884.

The object of the present invention is to increase the utility of the above noted type of machine, by providing mechanism which is adapted to co-operate with the standard mechanism of the repeating machine in such a manner that the machine in addition to being capable of duplicating a string or set of previously punched cards, hole for hole, may be caused to function in a manner to transfer the holes of predetermined sections of each card of an original string to relatively different positions on the corresponding cards of a string reproduced from the original string of cards.

Utility of such an arrangement will be obvious to those familiar with the art of card punching, for example, in cases where the same design is to be produced at various positions in a fabric it will be necessary to cut the cards for such design but once and by using the mechanism forming the subject of the present invention, in connection with the repeating machine, additional cards may be cut to produce the said design at any desired position with respect to that occupied by the design as determined by the holes in the original set of cards.

Another advantage attending the use of the present invention in connection with a card repeater resides in the ability to take a string of cards that have been punched in a manner to produce a plain fabric, for example, and another set of cards punched to produce a relatively small design at various positions throughout a fabric and to produce from these two strings of original cards a third string of cards which will combine the design of the second said string of cards with the plain fabric according to the first string of cards, the plain fabric forming a background for the design.

Other objects of the invention and the description and operation of the mechanism will be more fully disclosed hereinafter, reference being had to the accompanying drawings, of which:

Fig. 1 is a longitudinal sectional elevation of a card-repeating machine showing the mechanism of the present invention operatively associated therewith;

Fig. 2 is an enlarged transverse sectional elevation taken on the line 2—2, Fig. 1, and showing the transfer box in full;

Fig. 3 is a fragmentary side elevation, partly in section, showing the transfer box in its initial position after being inserted into the machine;

Fig. 4 is a view similar to Fig. 3, but showing the transfer box in its final operative position; 60

Fig. 5 is a sectional elevation of the transfer box taken on the line 5—5, Fig. 2;

Fig. 6 is a sectional plan view of the transfer box taken on the line 6—6, Fig. 2;

Figs. 7, 8 and 9 respectively illustrate details 65 of the construction of the transfer box;

Fig. 10 illustrates an original card having holes arranged to produce a predetermined design in predetermined position on a fabric;

Fig. 11 illustrates a card reproduced from the 70 card illustrated in Fig. 10, with the holes arranged to produce the same design as that produced by the card shown in Fig. 10, but in a different position on the fabric as determined by the transferring of the holes in the card shown 75 in Fig. 10 in accordance with the tie-up in the transfer box illustrated in Figs. 5 and 6 of the drawings;

Fig. 12 illustrates another form of tie-up within 80 the transfer box;

Fig. 13 illustrates another original card; and

Fig. 14 illustrates a card reproduced from that shown in Fig. 13 when using the tie-up in the transfer box as illustrated in Fig. 12 of the drawings. 85

Referring to Fig. 1 of the drawings, the repeating machine comprises a main base 1 at one end of which is mounted, for vertical reciprocal movement, a die plate 2 provided with a number of punch openings 3 which correspond in number and position with the greatest number of hooks used in the jacquard mechanism of any conventional type of loom. Co-operating with each of the openings 3 in the die plate 2 is a punch 4, which is vertically slidably mounted in a guide 95 plate 5 and a stripper plate 6, between the lower face of which and the upper face of the die plate 2 a string of blank cards *x* which are to be punched passes.

Horizontally arranged for longitudinal sliding 100 movement above the upper ends of the punch rods 4 is a series of punch stops 10, each of which is slidably mounted in a fixed bearing plate 11, each stop being operated and controlled by a stop rod 12, the said stop rods being horizontally arranged in the upper end of the main base 1, one end of each rod being operatively connected to a punch stop 10 while the opposite end of each rod is slidably mounted in a suitable supporting grid 110 carried by the main base 1.

Secured to the main base 1 above the stop rods 12 is a top plate 16 from which vertically projects a relatively spaced pair of grids 17 and 18 respectively. Slidably mounted for longitudinal movement in a horizontal direction in the grids 17 and 18 is a series of selecting needles 20 which correspond in number to the stops 10, stop rods 12, and punches 4.

Each of the stop rods 12 is provided with an eye 21 for the reception of one end of an operating lever 22, the opposite end of which extends through an eye 23 formed in or carried by the selector needle 20 corresponding to the stop rod 12 with which the first said end of the lever 22 operates. Each of the levers 22 is pivotally mounted at 24 in the top plate 16.

Slidably mounted on the top plate 16 is a reciprocating frame 25, and extending transversely of the machine at one end of the series of selector needles 20, and rotatably carried by the reciprocating frame 25, is a card cylinder 26 around which passes a string of cards *y* which under ordinary circumstances would be duplicated by the repeating machine above described. Extending transversely of the machine and carried by the reciprocating frame 25 at the opposite ends of the selecting needles 20 is an evener 27.

Ordinarily the original string of previously punched cards *y* which is to be repeated is passed around the card cylinder 26 and a string of blank cards, such as illustrated at *x*, is fed between the stripper plate 6 and the die plate 2 when the said die plate is in a lowered position. The machine is operated in the manner disclosed in the above mentioned patent. The frame 25 is caused to move to the right, as viewed in Fig. 1 of the drawings, bringing the card which is disposed on the face of the cylinder 26 that lies substantially parallel to the ends of the selecting needles 20 into engagement with the said ends of the said needles. Obviously where a hole in the card is in alignment with a needle 20 the position of the said needle is not altered, consequently the punched stop 10 which is controlled by that particular needle, through the medium of a lever 22 and stop rod 12, remains in position above the punch 4 which the said stop controls, consequently as the die plate 2 with a blank card positioned thereon is raised the punch 4, being held stationary by its stop 10, passes through the blank card and punches a hole therein in the same position on the card *x* as the hole in the said card *y* on the cylinder 26.

In cases where a blank space in the card *y* is in alignment with one of the needles 20 the said needle will be moved longitudinally when the frame 25 moves to the right to bring the card *y* into contact with the adjacently disposed ends of the needles 20. Longitudinal movement of any one of the selector needles 20, to the right, will cause a rocking of the lever 22 associated therewith, which causes a longitudinal movement, to the left, of the stop rod 12 with which the opposite end of the lever 22 co-operates. The punch stop 10 controlled by said rod 12 will be moved, to the left, from its operative position above the punch 4 which the said stop controls, consequently when the die plate 2, with the blank card *x* thereon, rises the punch 4 will move vertically with the said card, resting on the top face thereof, without punching a hole in the said card.

In accordance with the principles of the present invention a supplementary base 101 is provided adjacent the main base 1. Slidably mount-

ed in the supplementary base 101 is a series of rods 112, corresponding in number and in position with the stop rods 12 of the repeating machine, the rods 112 being slidably supported in grids 115, 115a carried by the supplementary base 101. 80

Each of the rods 112 is provided with an eye 121 which is adapted to receive one end of a lever 122, the opposite end of which is positioned in an eye 123 carried by a supplementary selecting needle 120. The supplementary needles 120 correspond in number and position with the selecting needles 20 of the repeating machine and are slidably supported at their opposite ends by grids 117 and 118 respectively. Each of the levers 122 is pivotally mounted at 124 in a supplementary top plate 116 carried by the supplementary base 101. 85 90

Slidably mounted on the supplementary base 101 is a reciprocating frame 125. Carried by the reciprocating frame 125 and extending transversely of the machine adjacent and substantially parallel to the outer ends of the selecting needles 120 is a card cylinder 126 around which is adapted to pass an original punched string of cards *z*. At the opposite ends of the needles and carried by the reciprocating frame 125 is an evener 127. 95

In the present instance, the reciprocating frame 125 is operatively connected to the reciprocating frame 25 of the repeating machine and is operated synchronously therewith as the frame 25 is reciprocated by the mechanism of the repeating machine as disclosed in the above-mentioned patent. 105

Intermediate the base 1 and the supplementary base 101 is provided a transfer box 150 whereby the supplementary rods 112 may be operatively connected to the stop rods 12 of the repeating machine in a manner to effect duplication of the holes of the string of cards *z* in the blank cards *x*, or to transfer the position of the holes of the cards *z* to any desired position on the blank cards *x*, or whereby certain of the holes in the string of cards *z* may be eliminated from the blank cards *x* under control of the stop rods 12 by the string of cards *z* through the transfer box 150, all as will be more fully disclosed hereinafter. 110 115 120

The transfer box as shown in Figs. 3, 4, 5, 6 and 12 comprises end plates 151 and 152. Rigidly secured to the end plates 151 and 152 are side plates 153 and 154 respectively. The side plates 153 and 154 are provided with series of openings 155 and 156 respectively, which correspond in number and position with the stop rods 12 of the repeating machine and the rods 112 of the supplementary mechanism. 125 130

In each of the openings 155 in the side plate 153 is slidably mounted a hook element 157 and in each of the openings 156 in the side plate 154 is slidably mounted a hook element 158, the said hook elements being shown in detail in Fig. 7. 135

Each of the hook elements is preferably composed of a circular rod having a notch 159 formed adjacent one end thereof, providing a shoulder 160 immediately adjacent the end of the said hook element. In order to prevent the hook elements 140 from rotating, but at the same time permitting longitudinal movement thereof, each hook element is provided with a lug 161 extending laterally therefrom in the plane of the body of the hook element. The lugs 161 are adapted to be 145 disposed within grooves 162 formed in the inner faces of the side plates 153 and 154 respectively, the said grooves being clearly shown in detail in Fig. 8.

The lugs 161 also function as means for limit- 150

ing the longitudinal movement of the hook elements within the side plates in which the said hook elements are slidably mounted, one end of the lug 161 being adapted to bear against the base 5 surface 163 of the slot 162 in one position of the hook element, while the opposite end of the said lug is adapted to bear against a bearing plate 164 or 165 as the case may be, when the hook element is in another position.

10 The bearing plate 164 is secured to the inner face of the side plate 153 while the bearing plate 165 is secured to the inner face of the side plate 154, each of the plates 164 and 165 being provided with perforations 166 which are axially aligned 15 with the perforations 155 and 156 of the side plates 153 and 154 respectively, for receiving and supporting the hook elements 157 and 158.

Each of the hook elements 157 and 158 is reduced at its end opposite to that in which the 20 notch 159 is formed, as illustrated at 167, Fig. 7. The outer end of each of the reduced portions 167 is threaded at 168 for the reception of a nut or head 169 to which is attached one end of a connecting wire 170. The inner end of the nut or 25 head 169 on each hook element provides a shoulder 171 thereon while the reduction of the diameter of the portion 167 of the hook element with respect to the diameter of the body portion of said hook element provides a second shoulder 172 on 30 each hook element, for purposes hereinafter described.

Spaced inwardly from the bearing plate 164 is a second bearing plate 173 and on each of the hook elements 157 and encircling the reduced portion 35 167 thereof between the said bearing plate 173 and the shoulder 172 of the said hook element is a spring 174, which at all times tends to maintain the hook element 157 in its outermost position with respect to the side plate 153.

40 Spaced inwardly from the bearing plate 165 is a second bearing plate 175 and on each of the hook elements 158 and encircling the reduced portion 167 thereof between the said bearing plate 175 and the shoulder 171 is a spring 176, which tends 45 at all times to maintain the hook element 158 in its innermost position with respect to the side plate 154.

As shown in Fig. 6, the side plate 153, bearing plate 164 and the bearing plate 173 are secured 50 together by means of bolts 177 and the side plate 153 is secured to the end plate 151 and 152 by means of screws 178. The side plate 154, and the bearing plates 165 and 175 are secured together by bolts 179 and the side plate 154 is secured to 55 the end plates 151 and 152 by means of screws 180. By this arrangement the mechanisms carried by the side plates 153 and 154 respectively may be readily removed from the transfer box 150 as a unit for the purpose of assembling the hook elements 157 and 158 therein, or for making any desired 60 adjustments thereto.

Inwardly spaced from the bearing plates 173 and 175 and secured to the end plates 151 and 152 are guide plates 181 and 182 respectively. 65 These guide plates are provided with eyes 183 through which the connecting wires 170 pass, it being noted that the eyes 183 are suitably rounded in all directions to provide for smooth movement of the connecting wires 170, 170 regardless 70 of the angle assumed by the said wires intermediate the guide plates 181 and 182.

With the apparatus assembled as in Figs. 1 and 4, the rods 12 of the repeating machine and the rods 112 of the supplementary position are respectively and axially aligned with each other.

The hook elements 157 are axially aligned with the rods 12 of the repeating machine and the hook elements 158 in the transfer box are axially aligned with the rods 112 of the supplementary mechanism while the hook elements 157 and 158 of the transfer box are axially aligned with each other. 80

As shown in Figs. 1, 3 and 4, each of the rods 12 is notched in its upper side as illustrated at 184 providing a shoulder 185 adapted to co-operate with the shoulder 160 in the underside of the hook element 157 associated therewith and each of the rods 112 is notched in its upper side as indicated at 186 providing a shoulder 187 for co-operation with the shoulder 160 of the hook element 158 with which the said rod is associated. 85

The transfer box 150 is adapted to be readily removed from and inserted into the machine in order to provide for the making of various tie-ups between the hook elements 157 and 158 by the connecting wires 170, in order to transfer the positions of the holes in the string of cards *z*, for example, to other desired positions in the string of blank cards *x* to be reproduced from the said 100 string of cards *z*.

In order to permit the transfer box 150 to be readily inserted and removed from the machine the said box is provided with skids 190 and 191 disposed respectively on the underside of the box 105 adjacent the side plates 153 and 154 respectively, each skid having a high central portion 192 and a low portion 193 disposed at each side thereof and extending parallel to the high portion 192. The high portions 192 of the skids 190 and 191 110 are adapted to slide within grooves 194 formed in the frame 195 while the low portions 193 of the said skids ride on the upper surfaces of ribs or tracks 196 on the said frame 195 which are disposed at opposite sides of and form therebetween 115 the said grooves 194.

In order to insert the transfer box 150 into the machine or to remove the said box from the said machine the box must be raised sufficiently to permit the hook elements 157 and 158 to slide 120 between the horizontally disposed rows of rods 12 and 112 respectively, as illustrated in Fig. 3, and as the transfer box 150 is inserted in the machine the said box must be lowered in order to operatively connect the hook elements 157 and 158 with 125 the said rods 12 and 112 respectively. The frame 195 provides a suitable guide for the box 150 when the said box is being inserted or removed from the machine and the frame 195 is mounted in the machine in such a manner that it may be raised 130 and lowered to effect the above mentioned raising and lowering of the transfer box 150.

For the purpose of raising and lowering the frame 195 the said frame is provided at each side of each of its ends with laterally spaced depending bosses 196, 196 which are provided with vertically extending slots 197 through which extend horizontal shafts 198. On each shaft, intermediate each pair of the bosses 196, 196, is secured a cam or eccentric 199 which bears against a pad 140 200 formed on the frame 195 intermediate the said depending bosses 196. 135

Secured to the underside of the frame 195 intermediate the shafts 198, 198 is a bow spring 201, the opposite ends of which bear on the under- 140 sides of the shafts 198, 198 respectively, tending at all times to lower the frame 195 and maintain contact between the eccentrics 199 and the bearing pads 200.

The shafts 198, 198 are rotatably mounted in 150

bearings 202, 202 which are adjustably secured to bars 203, 203 carried by the main base 1 of the repeating machine and the supplementary base 101 of the co-operating apparatus respectively. 5 Each shaft 198 in the present instance is provided with a worm wheel 204 which meshes with a worm 205 secured to a shaft 206 which is mounted in suitable bearings 207 in the present instance carried by bearings 202 at one side of the transfer box 150. Secured to one end of the shaft 206 is an operating handle 208 by which the shaft 206 may be rotated to raise and lower the frame 195.

In order to effect axial alignment between the 15 rods 12 and the hook elements 157 of the transfer box 150 and between the rods 112 and the hook elements 158 of the said transfer box the frame 195 is provided with a relatively fixed but adjustable abutment 210 against which one end 20 of the transfer box is adapted to rest, a pad 211 being provided on the end plate 151 of the transfer box 150 for that purpose. The opposite end of the transfer box 150 is provided with a locking cam 212 which is rotatably mounted at 213 on the 25 end plate 152 of the transfer box 150, the cam 212 engaging a lug 214 formed on the frame 195 and being provided with a handle 215 by which the said cam may be rotated to bring the inclined cam surface 216 thereof into locking contact with the inner face of the lug 214 on the frame 195, whereby the transfer box 150 will be moved into contact with the relatively fixed abutment 210 on the frame 195 and the axial alignment of the hook elements 157 and 158 of the transfer box 150 with the rods 12 and 112 30 respectively is effected.

With the frame 195 in the raised position shown in Fig. 3, rotation of the shaft 106 will cause the said frame, and consequently the transfer box 150, to be lowered until the shoulders of 40 said hook elements lie behind the shoulders on the rods with which they co-operate.

To those familiar with the art of weaving and card punching it is well known that in some cases 45 a single card in a string thereof controls all the warp ends in a loom to raise some of the warp ends while permitting others to remain down in order to form a single continuous line of spots on the face of the fabric extending across the fabric from selavage to selavage thereof, while in other cases two or more of the cards are arranged in 50 end to end relation to each other on the cylinder of the jacquard mechanism of the loom to control the warp ends in forming the single line of face spots across the fabric from selavage to selavage thereof.

In either case the positioning of the holes in each card determines the color combination and positioning of the warp ends that will be raised 55 by that card to produce its particular line of variously colored face spots on the fabric.

In different looms the harnesses are tied up to the hooks of the jacquard mechanism in different manners, well known to the art, but regardless of the harness tie-up each card performs the same function as noted above.

It will therefore be quite obvious that if the 60 position of a certain group of holes in an original card, which controls a predetermined part of the line of face spots on the fabric, is altered in a card reproduced from the said original card the position of the spots in the fabric will be correspondingly altered when the reproduced cards are used in a loom, thus by the use of the mechanism above described the position of a de-

sign in the fabric may be changed as desired by properly connecting the hook elements 158 with the hook elements 157 in the transfer box 150, such connections being formed by the wires or other suitable flexible elements 170.

For the purpose of illustration, Fig. 10 illustrates an original card capable of receiving 756 holes. These holes are divided into blocks or sections A, B, C and D respectively, each section being adapted to control the warp ends of a predetermined part of the fabric. Punching holes at various positions within the area of each of these sections in successive cards brings up the different warp ends in the weaving so that a predetermined design is depicted in a predetermined position on the face of the fabric.

Fig. 11 illustrates a card reproduced from the card shown in Fig. 10. In Fig. 11 the hole sections A, B, C and D are bodily shifted with respect to the positions they held in the original card so that the design unit controlled by the holes in each of these sections will be shifted in the fabric in the same general way as the sections of holes are shifted in the cards.

This shifting of the hole sections is effected by 100 connecting the hook elements 158 of the transfer box 150 with the hook elements 157 thereof as illustrated in Figs. 5 and 6.

The block of hook elements 158, designated as A¹ in Fig. 6, is connected to the block of hook elements 157, designated as A²; the block B¹ with the block B²; the block C¹ with the block C²; the block D¹ with the block D².

When the transfer box, having this tie up, is placed in the machine and the string of cards z, 110 including the card shown in Fig. 10, is placed on the cylinder 126, the hook elements 158 in the block A¹ register with a corresponding block of the supplementary rods 112 and these in turn are operatively connected with a corresponding 115 block of the supplementary selector needles 120 which register with the hole section A of the cards in the string z. The block of hook elements 157 which is designated as A¹ register with a corresponding block of the stop rods 12 in the 120 repeating machine and these in turn control the punch stops 10 of a block of the punches 4 which correspond in position to the position of the hole section A of the card shown in Fig. 11.

The other blocks of hook elements B¹—B², 125 C¹—C² and D¹—D² co-operate with the rods 12 and 112 in a similar manner to that just described with respect to the blocks A¹—A².

Thus with the transfer box 150 in place and upon starting the repeating machine the frame 130 125 will move to the right, with the card shown in Fig. 10, for example, in operating position on the cylinder 126. Where no holes appear in the operating card of the string z the corresponding supplementary needles 120 will be moved 135 to the right and through their levers 122 will move the corresponding rods 112 to the left. These rods in turn being connected to the hook elements 158 of the transfer box 150 will pull the corresponding hook elements outwardly from 140 the box 150. The pulled hook elements 158 being connected to corresponding hook elements 157 at the opposite side of the transfer box 150 by the connectors 170 will pull the said hook elements 157 inwardly with respect to the box 150. The hook elements 157 being operatively connected to the stop rods 12 and the stop rods 12 being connected to the stops 10 will cause the stops 10 to be moved out of line with their punches 4, thus when the die plate 2 rises with 145 150

4 a card thereon the free punches will ride up with the card while the remaining punches are held against vertical movement by their stops 10, thus the card of the string x then resting on the die 5 plate 2 will be punched in the manner illustrated in Fig. 11, a duplicate of the card shown in Fig. 10 with the exception that the positions of the hole sections A, B, C and D are altered, to correspondingly alter the position of the design 10 in the fabric.

It will be here noted that the reproduced string 15 of cards x may be tied up with the original string z for use in a loom so that the finished fabric will in one place have the design positioned according to the card shown in Fig. 10 and in another place positioned according to the card 20 shown in Fig. 11. Obviously, the same design may be made to appear at any desired number of different positions on the fabric by changing the tie up in the transfer box 150 for each position desired and then including the string of reproduced cards in the string to be used in the loom.

The cards shown in Figs. 10 and 11 did not 25 require the use of the entire number of punches in the repeating machine, therefore, the end blocks of hook elements 158 designated as F^1 and G^1 in Fig. 6 are tied up with the blocks of hook elements 157 disposed in direct axial alignment therewith and indicated at F^2 and G^2 respectively, consequently when the corresponding blocks of supplementary needles 120 engage the blank ends F and G of the cards z on the cylinder 126 the corresponding punches 4 will be 30 freed and will leave the corresponding ends of the cards of the string x blank.

In Figs. 13 and 14 cards are shown which require the use of the full complement of punches in the repeating machine. In reproducing the 40 card shown in Fig. 14 from the card shown in Fig. 13 the tie up in the transfer box 150, such as shown in Fig. 12, is employed. In this instance the positions of the holes in sections H and I of the card shown in Fig. 10 have been bodily 45 moved from one side of the center line $c-c$ to the other side of the said center line of the card as shown in Fig. 14.

Where it is desired to place a small design, for 50 example, on a plain background and the cards for the plain fabric have already been cut, such string of card may be placed on the cylinder 26 of the repeating machine as shown at y and another string of card cut for the small design may be placed on the cylinder 126 as shown at z .

55 When the machine is operated and the cards y co-operating with the selector needles 20 function to punch holes in the card of the string x then on the die plate 2 to bring up spots of one solid color on the face of the fabric, the cards 60 of the string z co-operating with the selector needles 120, rods 112, transfer box 150 and rods 12 will function to countermand in part the selection made by the cards y through the selector needles 20 so that in place of the solid color spots 65 coming up in the finished fabric entirely across the fabric a small design according to the cards z will be depicted on the fabric.

In this case the tie-up in the transfer box would be in direct axial alignment between the hook 70 elements 158 and 157, similar to that shown at F^1-F^2 and G^1-G^2 in Fig. 6.

With the straight across tie-up in the transfer box as noted above, the machine may be used 75 purely as a repeater by placing the original string of cards, that is to be duplicated, on the cylin-

der 126, or by placing the original string of cards on the cylinder 26 and removing the transfer box 150 completely from the machine.

While but three different tie-ups for the transfer box have been disclosed, for the purpose of illustration, it will be obvious that the hook elements 158 and 157 may be connected in any manner desired to get any desired ultimate result from either one or two original strings of cards, in addition to using the machine as a straight repeater.

If desired, the tie-up in the transfer box may be such that any one of the pull hooks 158 may be tied up to a plurality of the pull hooks 157 so that one hole in the original card may be caused to effect the punching of a number of holes in the reproduced card, for example a corresponding hole in each of the different sections of the card.

I claim:

1. In a card punching machine, the combination of a series of punches arranged in invariable order, a series of selector elements arranged in a corresponding invariable order for controlling said punches in accordance with a pre-arranged order of holes in an original card co-operating with the selector elements for reproducing the holes of said original card in a reproduced card in the same invariable order as they appear in said original card, a supplementary series of selector elements arranged in substantially the same invariable order as the first said series of selector elements for co-operation with prearranged holes in a second original card, and means operatively connecting the supplementary selector elements with said punches for supplementary control of said punches whereby the holes in the reproduced card will be punched in an order determined by the combination of the holes of the two said original cards.

2. In a card punching machine, the combination of a series of punches arranged in invariable order, a series of rods arranged in a corresponding order for respectively controlling said punches, a supplementary series of rods arranged in the same order as the first said series of rods, a series of selector elements operatively connected to and arranged in the same order as said supplementary rods, said selector elements being adapted to co-operate with an original card having holes arranged in a predetermined order, a transfer device intermediate the two said series of rods and including means arranged to be detachably connected to the rods of the first said series respectively, means arranged to be detachably connected to the rods of the said supplementary series respectively, and means for connecting the said detachable connecting means of the two said series of rods in any desired order for reproducing the holes of the original card in a second card in any desired order with respect to the holes of the original card.

3. In a card punching machine, the combination of a series of punches arranged in invariable order, a series of rods arranged in a corresponding order for respectively controlling said punches, a supplementary series of rods arranged in the same order as and substantially in axial alignment with the rods of the first said series respectively, a series of selector elements arranged in the same order as the supplementary rods and respectively connected thereto, said selector elements being adapted to co-operate with an original card having holes arranged in a predetermined order, a transfer box disposed inter-

mediate the ends of the two said series of rods, a series of elements protruding from each of the opposite sides of the transfer box and arranged in the same order as and in substantial axial alignment with the two said series of rods respectively, means for detachably connecting the said rods with the said protruding elements respectively and means in the transfer box for respectively connecting the said protruding elements of opposite sides of the transfer box in any desired order, for reproducing the holes of the original card in a second card in any desired order with respect to the holes of the original card.

15 4. In a card punching machine, the combination of a series of punches arranged in invariable order, a series of rods arranged in a corresponding order for respectively controlling said punches, a supplementary series of rods arranged in the same order as and substantially in axial alignment with the rods of the first said series respectively, a series of selector elements arranged in the same order as the supplementary rods and respectively connected thereto, said selector elements being adapted to co-operate with an original card having holes arranged in a predetermined order, a transfer box disposed intermediate the ends of the two said series of rods, a series of elements protruding from each of the opposite sides of the transfer box and arranged in the same order as and in substantial axial alignment with the two said series of rods respectively, means for detachably connecting the said rods with the said protruding elements respectively, means in the transfer box for respectively connecting the said protruding elements of opposite sides of the transfer box in any desired order, for reproducing the holes of the original card in a second card in any desired order with respect to the holes of the original card, and means for removably supporting the transfer box intermediate the ends of the two said series of rods.

45 5. In a card punching machine, the combination of a series of punches arranged in invariable order, a series of rods arranged in a corresponding order for respectively controlling said punches, a supplementary series of rods arranged in the same order as and substantially in axial alignment with the rods of the first said series respectively, a series of selector elements arranged in the same order as the supplementary rods and respectively connected thereto, said selector elements being adapted to co-operate with an original card having holes arranged in a predetermined order, a transfer box disposed intermediate the ends of the two said series of rods, a series of elements protruding from each of the opposite sides of the transfer box and arranged in the same order as and in substantial axial alignment with the two said series of rods respectively, co-operating hooks on the ends of the said rods and protruding elements respectively for detachably connecting the said rods with the said protruding elements respectively, means in the transfer box for respectively connecting the said protruding elements of opposite sides of the transfer box in any desired order, for reproducing the holes of the original card in a second card in any desired order with respect to the holes of the original card, means for removably supporting the transfer box intermediate the ends of the two said series of rods, and means for raising and lowering the transfer box for disconnecting the

said hooks to permit removal of the said transfer box.

6. In a card punching machine, the combination of a series of punches, a series of rods for controlling said punches, a series of selector needles operatively connected to said control rods, a card support adjacent one end of said selector needles for supporting an original card in operative relation to said needles, a supplementary series of selector needles, a card support adjacent one end of said supplementary series of needles for supporting an original card in operative relation thereto, a supplementary set of control rods operatively connected to the said supplementary series of selector needles, and means intermediate the two said series of control rods for selectively connecting the rods of said series respectively. 80 85 90

7. In a card punching machine, the combination of a series of punches, a series of rods for controlling said punches, a series of selector needles operatively connected to said control rods, a card support adjacent one end of said selector needles for supporting an original card in operative relation to said needles, a supplementary series of selector needles, a card support adjacent one end of said supplementary series of needles for supporting an original card in operative relation thereto, a supplementary set of control rods axially aligned with the rods of the first said series respectively and operatively connected to the said supplementary series of selector needles, and means intermediate the two said series of control rods for selectively connecting the rods of said series respectively. 95 100 105

8. In a card punching machine, the combination of a series of punches, a series of rods for controlling said punches, a series of selector needles operatively connected to said control rods, a card support adjacent one end of said selector needles for supporting an original card in operative relation to said needles, a supplementary series of selector needles axially aligned with the needles of the first said series, a card support adjacent one end of said supplementary series of needles for supporting an original card in operative relation thereto, a supplementary set of control rods axially aligned with the rods of the first said series respectively and operatively connected to the said supplementary series of selector needles, and means intermediate the two said series of control rods for selectively connecting the rods of said series respectively. 110 115 120 125

9. In a card punching machine, the combination of a series of punches, a series of rods for controlling said punches, a series of selector needles operatively connected to said control rods, a card support adjacent one end of said selector needles for supporting an original card in operative relation to said needles, a supplementary series of selector needles axially aligned with the needles of the first said series, a card support adjacent one end of said supplementary series of needles for supporting an original card in operative relation thereto, a supplementary set of control rods axially aligned with the rods of the first said series respectively and operatively connected to the said supplementary series of selector needles, means intermediate the two said series of control rods for selectively connecting the rods of said series respectively, and a reciprocating frame for supporting and simultaneously operating the two said card supports with respect to the two said series of needles respectively. 130 135 140 145

10. In a card punching machine, the combina- 150

- tion of a series of punches, a series of rods for controlling said punches, a series of selector needles operatively connected to said control rods, a card support adjacent one end of said selector needles for supporting an original card in operative relation to said needles, a supplementary series of selector needles axially aligned with the needles of the first said series, a card support adjacent one end of said supplementary series of needles for supporting an original card in operative relation thereto, a supplementary set of control rods axially aligned with the rods of the first said series respectively and operatively connected to the said supplementary series of selector needles, means intermediate the two said series of control rods for selectively connecting the rods of said series respectively, a reciprocating frame for supporting and simultaneously operating the two said card supports with respect to the two said series of needles respectively, and an evener at the opposite end of each series of needles and carried by the said reciprocating frame.
11. In a card punching machine, the combination of two independent series of punch control rods arranged respectively in invariable orders and adapted for actuation by independent cards having perforations predeterminedly arranged thereon, and a transfer device intermediate the two said series of rods and including mechanically actuatable means for operatively connecting the rods of the two said series in any desired order for combining perforations of said independent cards in predetermined positions on a single card.
12. In a card punching machine, the combination of two independent series of punch control rods arranged respectively in invariable orders and in axial aligned spaced relation to each other, a transfer box intermediate the spaced ends of the two said series of rods, elements protruding from each of the opposite sides of the transfer box in axial alignment with each other and with the rods of the two said series respectively, means for respectively connecting the said protruding elements with the said rods, and means in the said transfer box for connecting the said protruding elements in any desired order.
13. In a card punching machine, the combination of two independent axially aligned series of punch control rods arranged in spaced invariable order with respect to each other, a transfer box intermediate the spaced ends of said rods, a series of elements protruding from each side of the transfer box in axial alignment with and operatively connected to the adjacent series of rods,
- means within the box for resiliently maintaining each protruding element in a normal position with respect to the box, and flexible means within the box for selectively connecting the protruding elements of the opposite sides of the box respectively.
14. In a card punching machine, the combination of two independent axially aligned series of punch control rods arranged in spaced invariable order with respect to each other, a transfer box intermediate the spaced ends of said rods, a series of elements protruding from each side of the transfer box in axial alignment with and operatively connected to the adjacent series of rods, means within the box for resiliently maintaining each protruding element in a normal position with respect to the box, flexible means within the box for selectively connecting the protruding elements of the opposite sides of the box respectively, and guiding means for said flexible connecting means within said box.
15. In a card punching machine, the combination of two independent and axially aligned series of punch control rods arranged in longitudinally spaced relation to each other, a removable transfer box intermediate the spaced ends of said rods, a series of elements protruding from each side of said box for operative engagement in axial alignment with the adjacent series of rods respectively, means within the box for selectively connecting the said protruding elements of the opposite sides of the box, and means for effecting said axial alignment of said protruding elements with said rods respectively.
16. In a card punching machine, the combination of two independent and axially aligned series of punch control rods arranged in longitudinally spaced relation to each other, a removable transfer box intermediate the spaced ends of said rods, a series of elements protruding from each side of said box for operative engagement in axial alignment with the adjacent series of rods respectively, means within the box for selectively connecting the said protruding elements of the opposite sides of the box, a shoulder on each rod, a shoulder on the aligned protruding element for operative engagement therewith, a frame for removably supporting the box, means for positioning the box in definite relation to the frame to effect lateral alignment of the shoulders of the protruding elements with the shoulders of the rods, and means for raising and lowering the frame to effect horizontal alignment between said shoulders.
